UNITED STATES PATENT OFFICE.

ANNIE Y. CRISSEY, OF GALESBURG, ILLINOIS.

BED-PAN.

1,124,709.

Specification of Letters Patent.

Patented Jan. 12, 1915.

Application filed April 14, 1914. Serial No. 831,726.

To all whom it may concern:

Be it known that I, ANNIE Y. CRISSEY, a citizen of the United States, and a resident of Galesburg, in the county of Knox and State of Illinois, have invented a new and useful Bed-Pan, of which the following is a specification.

My present invention relates to bed-pans of that character which are composed of two parts, to-wit: a bed-pan proper or receptacle, and a support therefor, and it is purposed as an improvement over the one disclosed in my co-pending application Serial No. 801,536, allowed February 11, 1914.

In the present invention I have shown a bed-pan proper which may be constructed of stable or permanent material, such as metal, or of destructible material, such as paper, pressed, molded or otherwise formed and preferably paraffined or in some other manner made waterproof and combustible.

In my former device it was necessary, in order to remove the discharge-containing receptacle, that both members of the pan be removed, and in so doing there was always liability that the contents would be spilled onto the bed clothing. This, in fact, is a fault common to all devices which have hitherto come under my observation.

The principal object of the present invention is to provide a bed-pan one (the receptacle or pan-proper) part of which may be freely slid from under the patient, the other portion being meanwhile left where operatively positioned, to support him, in order not only to remove the pan and its contents, but further that the patient may be properly cleansed.

In this connection a subsidiary object is to omit the front end of the supporting member, in order that the hand may be readily introduced thereinto. It may be here stated also that by leaving the front end of the pan entirely free and unobstructed and by employing it in combination with a pan-receiving and body-supporting member provided with a centrally cutaway portion at its front end, a syringe may be introduced without turning the patient on his side or otherwise disturbing him—a thing which cannot be done when an ordinary bed pan is used. Other advantages accruing from the use of a pan which slides horizontally with reference to and into the pouch are that the attendant does not have to exert strength in lifting or turning the patient with one

hand and arm while removing the pan with the other; the removal of the pan proper may be expeditiously accomplished: and it is accomplished without exertion on the part of the patient.

Another object is to so construct the pan proper and its lid or cover that the latter may be either placed in position or removed therefrom while the patient is resting on the support and the pan in position therein.

Still another object is to provide a pouch which is at once comfortable for the patient as he rests thereon and which may be quickly and easily placed under and removed from under him.

Another object is to generally improve the construction and increase the utility of apparatus of this character.

The invention consists, substantially, in the constructions and combinations herein-after described and claimed.

In carrying out the objects of the invention, generally stated above, it will be understood of course that the essential features of the same are susceptible of various changes in details, structure, and structural arrangements, certain practical and preferred embodiments of which are shown in the accompanying drawings, wherein:

Figure 1 is a longitudinal, vertical central section, partly in elevation and partly broken away; Fig. 2, a reduced modification, a side elevation partly broken away and partly in section; Fig. 3, a top plan, partly broken away and partly in section, the plane thereof being taken in the line $x-x$ in Fig. 1; Fig. 4, another reduced modification; and Fig. 5 a reduced, modified form of pan and cover.

Referring to each element and, where necessary, to each part thereof by a distinguishing reference numeral, uniformly employed, 2 designates a supporting element or pouch. Its lower portion comprises a bottom 3, sides 4 and rear end portion 5. These are preferably stamped from a sheet of metal, and the upper edge of the wall is crimped as shown at 6 where it is engaged by the lower edge of the pouch top 10 which also is formed preferably of a sheet of metal bent into proper form. It is cut away at its forward median portion to provide cheeks 7 which constitute buttock supports, these being spaced from each other.

I prefer to extend the forward end of the floor or bottom 3 well forwardly of the

top 10 (which of course is to be considered as a portion of the pouch) in order not only that its relatively large size will to a great extent eliminate any tendency to tip, but 5 further in order that it will act as a support for the front end of an oblong bed-pan proper (or receptacle) 9, which is preferably stamped, pressed, or molded from waterproof material having a sufficiency of 10 stability or rigidity not only to maintain a permanent shape but also to support itself and its contents when filled with such matter as it is adapted to contain in use. For 15 these purposes paraffined paper is especially adapted, for it is economic of manufacture and entails but a nominal loss when destroyed. It is to be distinctly understood, however, that the pan may be of metal or any other suitable material, the fact that it 20 is preferably constructed of paper being merely subsidiary to the main object of the invention.

The relative proportions of the elements and parts thereof hereinbefore described, 25 especially as regards their heights, may be varied at will, as will be noted by a comparison of Figs. 1 and 2, the pan shown in the latter being much deeper than the one depicted in the other. And in order that 30 the pans may be nested for shipment and storage they may be made tapering, as shown in Fig. 2. It is unnecessary that the pouches be nested, as they being permanent will not be purchased, shipped or carried 35 in stock in any such relatively great quantities as will be the destroyable pans.

In Figs. 1 and 3 I have shown the rear portion 11 of the rim of the pan 9 to be bent to form a channel 12, shown best in Fig. 1. 40 13 indicates a lid or cover the parallel edges of which are adapted to slide in confronting channels 12 and its rear end curved and adapted to fit snugly in the rear channel portion.

45 Fig. 2 illustrates the pouch 2 as made integral or without seams, as in the case of pottery.

Fig. 4 illustrates a similar pouch containing a pan differing greatly in construction 50 from those shown elsewhere in the drawings. This pan and its cover are shown more fully in Fig. 5 wherein are illustrated a very simple form of oblong rectangular box-like pan 9' and a lid therefor comprising 55 a top 14 having depending sides 15 and one depending end, 16, the usual opposite end being omitted in order that the lid may be slid into place while the pan is positioned within the pouch.

60 In each of Figs. 1, 3 and 4 I have shown the front end of the bottom or floor 3 of the pouch as provided with a hole 18 whereby it may be hung upon a nail or sustained by a cord passed therethrough.

65 In operation, the attendant will place the

pouch or support beneath the patient in the same manner as he would a bed-pan of ordinary type. The pan proper may be then slid horizontally through the open front end of the pouch and thereinto, the bottom 3 70 affording a smooth plane surface over which it will slide with the utmost freedom. The cheeks 7 (which include that portion of the top which is rearmost) cover a large portion of the rear part of the pan and provide 75 an easy rest or support for the buttocks of the patient. When it is desired to remove the pan the lid may be quickly and freely slipped into place to entirely cover and practically seal the contents of the pan, and 80 it is to be particularly noted that this may be done while the patient is resting on the pouch and the pan in place therein. The lid having been thus positioned, the flange 11 affords a convenient means for grasping 85 the pan and simultaneously the lid when it is desired to withdraw them from the pouch, which also may be freely done without in any manner disturbing the patient. Any of the attentions which it is usual to 90 give a patient either previous to or after the actual uses of the pan, are facilitated by the use of the open-end support herein described and shown, for the attendant's arm may be freely introduced through the 95 centrally cutaway portion into the body-supporting member—a thing practically impossible to do where a closed-end support or one devoid of the centrally cutaway portion is used, for the vertically rising wall of 100 the former, or the solid, and therefore projecting, top of the latter, would utterly preclude the free introduction of the hand and arm into the support. The same manner of operation is followed when the devices 105 shown in the modifications are employed.

It has not been thought necessary to enter into more minute detail in reference to some of the advantages accruing from the constructions shown, for it is believed that these 110 will be apparent.

Having thus described the preferred structures embodied in my invention and having set forth its nature and purposes, I claim as new and desire to secure by Letters Patent the following, namely:

1. A device of the character described comprising a pouch having an open and a closed end, a bed-pan adapted to be slid into said pouch through said open end and to be partly covered by said pouch, and a lid adapted to be slid into position to cover said pan when the latter is in its operative position within the pouch.

2. A device of the character described comprising a pouch having an open end and a partly covered top, a bed-pan adapted to be slid horizontally into said pouch through said open end and to be partly covered by said top, and a lid adapted to 125

be slid onto said pan while the latter is in its normal position in the pouch.

3. The combination with a support for a bed-pan and for the buttocks of a person, of a bed-pan adapted to be positioned partly within said support while the person is resting thereon, and a lid adapted to be positioned on said pan while the person is rest-

ing on said support and the pan in place therein.

In testimony whereof I hereunto set my hand this 3rd day of April, 1914.

ANNIE Y. CRISSEY.
